VALVE STEM GRINDING AND FITTING
DEVICE

Michael Holhut and Walter G. Vollmer, St. Louis,
Mo., assignors to H & H Machine & Motor
Parts Co., St. Louis, Mo., a corporation of
Missouri

Application September 16, 1936, Serial No. 101,005

7 Claims. (Cl. 51—124)

This invention relates generally to valve-stem grinding and fitting devices and, more particularly, to a certain new and useful improvement in devices especially adapted for gauging and grinding the tappet-engaging ends of automobile valve-stems.

Our invention has for its primary object the provision of a device of the type stated so constructed for accurately gauging the length of automotive and other types of valve-stems and grinding the stems precisely to the desired length.

Our invention has for a further object the provision of a device of the type stated in which the desired valve-stem length may be precisely gauged and set directly upon the jig or fixture for valve-stem grinding.

Our invention has for another object the provision of a device of the kind and for the purpose stated, which is of simple structure, durable and efficient in operation, and rapid and convenient in manipulation.

And with the above and other objects in view, our invention resides in the novel features of form, construction, arrangement, and combination of parts presently described and pointed out in the claims.

In the accompanying drawings (two sheets):—

Figure 1 is a front elevational view of a valve-stem gauge and grinder constructed in accordance with our present invention;

Figure 2 is an end elevational view of the structure;

Figure 3 is a schematic sectional view of the jig for gauging and holding the valve-stem for grinding operation, the jig being shown in position for stem gauging and setting relatively to the automotive valve-seat and tappet assembly;

Figure 4 is a side elevational view of the pilot gauge forming part of the present structure;

Figure 5 is an end elevational view of the jig shown in Figure 3;

Figure 6 is a fragmentary sectional view of the jig shown in Figures 3 and 5, taken approximately on the line 6—6, Figure 5;

Figure 7 is a fragmentary sectional view of the movable fixture of the valve-stem grinder, taken approximately along the line 7—7, Figure 2;

Figure 8 is a fragmentary sectional view of the movable fixture shown in Figure 7, taken approximately on the line 8—8, Figure 7;

Figure 9 is a fragmentary end elevational view of the movable fixture shown in Figure 7, showing in particular a detail of the jig holding member of the fixture; and

Figure 10 is a partially broken perspective view

of the jig shown in Figures 3 and 5, showing a valve-stem in operative position therein.

Referring now in more detail and by reference characters to the drawings, which illustrate a preferred embodiment of our present invention, the valve-stem grinder comprises a motor driven grinder wheel assembly A, a movable fixture B, and a valve-stem holding and gauging jig C for embracingly supporting an automotive cylinder valve D.

The grinder wheel assembly A includes preferably an electric motor or other prime mover mounted rigidly on a base 2 and operably connected through a manually or otherwise actuated switch 3 and a flexible electric conduit 4 in a conventional manner to a suitable source of power, not shown, the motor-shaft 5 being equipped at one projecting end with a face grinder or abrading wheel 6 and at its opposite projecting end with a second grinder or abrading wheel, wire brush, buffering wheel, or suitable or analogous member 7.

Preferably integrally formed on the base 2, is a pair of suitably spaced upstanding bosses or standards 8 transversely apertured in registration for, and to which by set-screws 9 is secured, a shaft 10 disposed accurately in a line parallel to the axial line of the motor-shaft 5.

Shiftably mounted on shaft 10 in a manner and for a purpose presently described, is the movable fixture B, which comprises an upwardly presented body-section 11 formed preferably integrally at its lower extremity with a longitudinally extending bottom-shell or housing 12 and at its upper extremity with a jig-holder 13, which latter, in turn, is formed with a first jig-engaging shoulder 14 provided in its upper face with an upwardly presented preferably serrated V-shaped recess, as at 14', a circularly recessed second jig-supporting shoulder 15 likewise provided in its upper face with an upwardly presented annular recess, as at 15', and intermediate the shoulders 14, 15, with an upstanding jig-positioning tongue 16, all as best seen in Figures 1 and 7, the shoulders 14, 15, being aligned perpendicularly to the true cutting plane of the face grinding wheel 6.

Forming part of, and disposed within, the shell or housing 12, is a pair of downwardly presented bosses 17, 17', having axially registering openings 18 for rotatably and shiftably engaging the shaft 10, the housing 12 in its forward end-wall 19 being provided with an opening 20 axially aligned with the openings 18 for freely and loosely accommodating the housing for shiftable move-

ment on the forwardly extended end-portion of the shaft 10. Formed in the opposite end wall 21 of housing 12 and also axially aligned with the openings 18, 20, and the shaft 10, is an internally threaded aperture 22 for adjustably receiving a fixture positioning-screw 23 abuttingly engageable at its inner extremity with the rear end of the shaft 10 and having at its outer extremity a knurled actuating-knob 24, a lock-nut 25 being preferably disposed about the screw 23 between the knob 24 and an outwardly facing shoulder 26 of the housing end-wall 21 for releasably retaining the screw 23 in adjusted position.

15 Suitably fixed on the shaft 10 within the housing 12 and positioned intermediate the standards 17, 17', is a collar 27, a helical spring 28 being coiled about and along the shaft 10 for impinging at its opposite ends against the standards 17 and collar 27, as also best seen in Figure 7.

20 Preferably integrally formed on, and disposed centrally of, the opposite lower margins of the base shell or housing 12, are outwardly presented ears 29, 30, for engaging shoulders 31, 32, respectively, upstanding from the base 2, as best seen in Figures 1 and 8, for limiting the rotative movement of the fixture B about the shaft 10.

25 Thus, it will be evident that the movable fixture B may be oscillated past the grinder wheel 6 in a plane parallel to a side face thereof from a position P' to a position P'', as shown in dotted lines in Figure 2, and may also be yieldingly shifted longitudinally upon and relatively to the fixed shaft 10 upon actuation of the positioning-screw 23, all for purposes presently more particularly appearing.

30 The valve-stem holding jig C comprises an outer, longitudinally split sleeve 33, which includes a valve-seating portion 34 and a stem-holding portion 35 substantially diametrically reduced relatively to, and by an intermediate frusto-conical valve-seat engaging portion 36 joined to, the valve-seating portion 34, which latter is provided at its outer end with a precisely machined frusto-conical seating face 34' for engagement with the seating face of an automotive cylinder valve D, as best seen in Figure 10.

35 Longitudinally disposed in the sleeve-portion 34 and opening at an end to the seat 34', is a pair of preferably diametrically opposite pockets 37, retained in which by dog-pointed screws 38 are compression-springs 39. Precisely fitting for longitudinal slide movement within the sleeve 33, is a split-tube 40 provided adjacent its one or so-called upper end with a pair of diametrically opposed pins 41 projecting radially outwardly into the pockets 37 through slots 42 for impinging engagement with the respective inner ends of the springs 39 for normally urging the tube 40 inwardly or downwardly within the sleeve 34, the tube 40 being also provided at its lower end with an inwardly presented valve-stem positioning and supporting shoulder 43.

40 Extending radially through the wall of the sleeve-portion 35, is an enlarged slot or opening 44 juxtaposed to a recess 45 extending radially inwardly from the outer peripheral face of the tube 40 and dimensioned accurately to fit tongue 46, the slot or opening 44 being of such size that the recess 45 will always be accessible to the tongue 46 regardless of the relative shifting of the tube 40 within the sleeve 33, as best seen in Figure 3.

45 Similarly extending radially through the side wall of the sleeve portion 34, is an internally

threaded opening 46, disposed in which is a manually operable set-screw 47 lockingly engageable with the tube 40 for a purpose presently described.

50 Co-operable with the jig C for gauging and setting the valve-stem length in a manner presently set forth, is a gauge-rod 51 preferably of greater length than the distance from the face 34' to the engine tappet 52, as shown in Figure 3, the rod 51 being provided at its one extremity 10 with a knurled knob 53 for facilitating manipulation and at its other extremity with a precisely machined tappet contacting foot 54. Preferably integrally and co-axially formed along the rod 51 at a precisely determined point for edgewise 15 abutment with an end face 55 of the shoulder 43, as will be presently explained, is an enlarged cylindrical portion 56 accurately diametrically sized to fit snugly within the forward end of the tube 40 for positioning the gauge rod 51 axially 20 within the jig C, as shown in Figure 3.

25 Also co-operable with the jig C for conjointly setting the jig C and the fixture B with respect to the grinder wheel 6, is a cylindrical pilot-gauge 57, best seen in Figure 4, precisely machined in all its dimensions and faces to fit abuttingly against the face 55 of the shoulder 43 coaxially within the tube 40 of the jig C, the length of the gauge 57, as designated by the distance xy in Figures 3 and 4, being exactly equal to the difference between the distance ac on the gauge rod 51 and the distance bd on the sleeve 33.

30 In setting the jig C for a valve grinding operation, the screw 47 is first loosened, so that the tube 40 and the sleeve 33 are free to slide relatively to each other, whereupon the springs 39, in their engagement with the pins 41, will yieldingly shift the tube 40 longitudinally downwardly relatively to the sleeve 33, so that the tube-shoulder 43 is at the maximum axial distance from the 40 valve-seat engaging face 34' on the sleeve 33. The gauge-rod 51 is then through the split 33' inserted co-axially in the jig C, so that the edge face of the portion 56 is in engagement with shoulder-face 55, whereupon the jig C is placed 45 in a selected valve opening of the internal combustion engine being assembled or repaired and the tappet-engaging foot 54 set firmly against the face of the tappet 52, as best seen in Figure 3.

45 When the distance from shoulder 43 to the valve-seat engaging face 36, designated as the distance cb , is greatest, the valve-seat engaging face 36 will stand away from the valve-seat of the engine; thus the sleeve 33 must be manually urged downwardly relatively to the tube 40 which 55 is now held in a fixed position relatively to the tappet 52 by means of the gauge-rod 51, the face 36 being thereby brought into tight, seated contact with the valve-seat of the engine, whereupon the screw 47 is tightened down against the tube 60 40, locking the tube 40 and sleeve 33 together in fixed relative position.

55 In such manner, a fixed setting of the distance cb is obtained on the jig in correspondence with the distance ab , which represents the true distance from the tappet-face to the valve-seat and likewise represents the precise length to which the valve-stem must be ground.

60 The jig C is then removed from the engine, the gauge-rod 51 also removed, and the pilot-gauge 57 inserted. As previously stated, the length xy of the pilot-gauge 57 is exactly equivalent to the difference between the distances ac and bd . Hence, it will be evident that the distance dx is exactly equivalent to the distance ab . 75

Thus, the outer face 58 of the pilot-gauge 57, which will be located on the line x, will exactly correspond to the true surface which must be ground on the valve-stem D.

5 The movable fixture B is oscillated in a counter-clockwise direction about the shaft 10 to the position indicated at P' in Figure 2. The jig C, with the pilot-gauge 57 in position, is then placed in the jig-engaging shoulders 14, 15, of the fixture 10 B, so that the tongue 16 thereof will fit into the recess 45 of the jig. The lock-nut 25 of the fixture B is loosened and the screw 23 rotated in the proper direction, thereby translating the fixture B longitudinally along the shaft 10 either 15 toward or away from the face of the grinding wheel 6, as the case may be, until the end face 58 of the pilot-gauge 57 is approximately in the plane of the face of the grinder wheel 6. The fixture B is then pivoted about the shaft 10 in 20 a clockwise direction until the entire jig C is in front of the face of the grinder wheel 6, as shown at P in Figure 2, whereupon the screw 23 of the fixture B is carefully turned to bring the end face 58 of the pilot-gauge 57 into accurate abut- 25 ment with the face of the grinder wheel 6, the lock-nut 25 being then tightened down on the locking shoulder 26 and the fixture B thus set in the desired position, it being obvious that the distance from the face 34' of the jig C to the 30 face of the grinder wheel 6 will exactly equal the true length to which the valve-stem D must be ground in order to snugly fit the selected valve chamber.

With the fixture B and jig C thus positioned, 35 the jig C is lifted out of the fixture, the pilot-gauge 57 removed, and the valve D inserted and manually held in such manner that the seating face of the valve is tightly pressed against the face 34' of the sleeve 33 and the stem is coaxially held within the tube 40 upon the shoulder 43. The jig C, thus carrying the valve D, is placed in the fixture B, as above described, the recess 45 of the jig C being brought into positioning engagement with the tongue 16 of the fixture B. The grinder wheel 6 is set into motion 40 and the entire jig-fixture assembly rotated back and forth around the shaft 10, thus bringing the tappet-engaging foot 54 of the valve-stem D into grinding contact with the grinder wheel 6 until the foot of the valve-stem will just clear the 45 face of the grinder wheel 6. The valve then will have been ground precisely and accurately to the desired length and may be removed from the jig for installation and assembly into the engine.

50 By our present invention, we thus provide an efficient device or structure in which valve-stems may be more economically, more speedily, and more accurately ground than has heretofore been possible, so far as we are aware, since the valve-holding jig C is set directly from the valve chamber to be accommodated, thus avoiding the time-wasting and error-producing operations of caliperizing the valve chamber and transferring the caliper measurement to a valve-stem holder.

55 The structure is relatively simple in structure, may be inexpensively constructed, the number of machined interfitting parts being materially reduced, with a consequent reduction in the costs of, and the number of possibilities for error in, machining, is durable and convenient in operative manipulation, and is efficient in the performance of its intended functions.

60 It will be understood that changes and modifications in the form, construction, arrangement, and combination of the several parts of the de-

vice or structure may be made and substituted for those herein shown and described without departing from the nature and principle of our present invention.

Having thus described our invention, what we 5 claim and desire to secure by Letters Patent is:—

1. In a valve-stem grinding and fitting device, in combination, a valve-stem holding jig comprising a sleeve, a tube longitudinally shiftable within the sleeve, the sleeve and tube being 10 arranged co-operatively for receiving a valve-stem and the sleeve having valve and valve-seat engaging faces, and means for securing the sleeve adjustably to the tube.

15 2. In a valve-stem grinding and fitting device, in combination, a valve-stem holding jig comprising a sleeve, a tube longitudinally shiftable within the sleeve, the sleeve and tube being arranged co-operatively for receiving a valve-stem and the sleeve having valve and valve-seat engaging faces, 20 a valve-stem supporting shoulder in the tube, and means for releasably locking the sleeve to the tube.

25 3. In a valve-stem grinding and fitting device, in combination, a valve-stem holding jig comprising a sleeve, a tube longitudinally shiftable within the sleeve, the sleeve and tube being arranged co-operatively for receiving a valve-stem and the sleeve having a valve and valve-seat engaging faces, 30 resilient means operatively disposed in the sleeve engageable with the tube for normally urging the tube longitudinally in a predetermined direction within the sleeve, and means for releasably locking the sleeve to the tube.

35 4. In a valve-stem grinding and fitting device, in combination, a base, a face abrasive disc mounted for rotation on the base, a unitary frame swingably mounted on said base for movement in a plane parallel to the face abrasive disc, said frame having integrally formed forward and rearward aligned jig-supporting yokes, and an integrally formed upstanding reference shoulder positioned intermediate of, and in alignment with, said yokes, and a removable valve-stem holding 40 jig operatively mountable in said yokes and having a transverse reference slot precisely engageable with the reference shoulder for positioning the jig longitudinally with respect to the frame for supporting a valve-stem for endwise engagement with the face of the abrasive disc.

45 5. In a valve-stem grinding and fitting device, in combination, a valve-stem holding jig comprising a sleeve, a tube longitudinally shiftable within the sleeve, the sleeve and tube being arranged co-operatively for receiving a valve-stem 50 and the sleeve having valve and valve-seat engaging faces, a pair of diametrically opposed longitudinally extending recesses formed in the sleeve, a pair of diametrically opposed radially outwardly extending pins rigidly mounted in the 55 tube for shiftable disposition within the sleeve recesses, and spring means disposed in each of the recesses in engagement with the pin for normally urging the tube toward a predetermined position with respect to the sleeve.

60 6. In a valve-stem grinding and fitting device, in combination, a valve-stem holding jig comprising a sleeve, a tube longitudinally shiftable within the sleeve, the sleeve and tube being arranged co-operatively for receiving a valve-stem 70 and the sleeve having valve and valve-seat engaging faces, a pair of diametrically opposed longitudinally extending recesses formed in the sleeve, a pair of diametrically opposed radially outwardly extending pins rigidly mounted in the 75

tube for shiftable disposition within the sleeve recesses, spring means disposed in each of the recesses in engagement with the pin for normally urging the tube toward a predetermined position with respect to the sleeve, and means threadedly disposed in each of the sleeve recesses engageable with the spring means for adjustably varying the tension thereof.

7. In a valve-stem grinding and fitting device, 10 in combination, a base, a face abrasive disc mounted for rotation on the base, a pair of up-standing bosses formed on the base and aligned at right angles to the face abrasive disc, a shaft mounted rigidly in and extending longi-

tudinally between said bosses, a unitary frame loosely mounted on said shaft for both swingable and longitudinally shiftable movement thereon, spring means mounted on the shaft in engagement with the frame for normally urging the frame 5 toward the face abrasive disc, and a set screw threadedly mounted in the frame in axial alignment and endwise abutting engagement with an end of the shaft for adjustably shifting the frame along the shaft to any predetermined position of adjustment.

MICHAEL HOLHUT.
WALTER G. VOLLMER.
